HEAT EXCHANGE CORE

Stanislaus Przyborowski, Kenmore, N. Y., assignor to Fedders-Quigan Corporation, Buffalo, N. Y., a corporation of New York

Application September 24, 1948, Serial No. 50,975

4 Claims. (Cl. 257—130)

1

This invention relates to a heat exchange apparatus, and it has particular reference to the provision of an improved fin and tube core particularly adapted for use as an automobile radiator, car heater, or the like.

More specifically, the present invention is concerned with an improved heat exchange core of the type wherein spaced tubes are positioned between spaced headers or manifolds, and fins interposed between the tubes and headers are formed by bending a strip of metal into generally zig-zag shape. A liquid, either relatively non-volatile, such as water, or highly volatile, such as a refrigerant, may be circulated through the tubes by inlet and outlet connections on the manifolds, to effect a heat exchange function with an air stream passing through the open gaps between the successive folds of the fin strips. Cores of this nature find application in the cooling of automotive engine coolants, heating the air in the car body, condensing hot compressed refrigerant vapor, and the like. The nature of the improvements, and the advantages attaching thereto, will be made apparent as this description proceeds, and the novelty will be pointed out in the appended claims.

In the drawings:

Fig. 1 is a generalized view of the rear face of the core as applied to an automobile engine radiator;

Fig. 2 is a side view of the radiator shown in Fig. 1;

Figs. 3 and 4 are enlarged fragmentary sections, taken on the line A—A of Fig. 2, and respectively showing modified forms of tube disposition;

Fig. 5 is a front elevation, on an enlarged scale, of a portion of an improved fin strip;

Fig. 6 is a view similar to Fig. 5, but showing a greater number of folds brought into closer proximity;

Fig. 7 is a view similar to Fig. 5, showing a modification in the formation of the fin strip;

Fig. 8 is a view, similar to Fig. 6, of the fin of Fig. 7 when compacted between a pair of spaced tubes; and

Fig. 9 is an enlarged fragmentary section through the center of the fin strip of either Figs. 5 or 7, and along the line B—B in Fig. 3.

The heat exchange core shown in Figs. 1 and 2 comprises a pair of spaced headers or manifolds 11 and 12 between which extend a plurality of parallel flat tubes 13. Fin ribbons, generally designated by the reference numeral 14, are bent back and forth on themselves to traverse the

2

spaces between adjacent tubes, and thus provide air passage cells. In the forms illustrated in Figs. 2, 3, and 4, the core is three tubes deep from face to face, but it should be understood that a greater or less number may be employed. The fins, tubes, and headers are connected to each other by dipping in a bath of molten solder, tinning and heating in a furnace, brazing, or the like, all of which is well understood. When assembled and integrated, liquid may flow into and out of the manifolds 11 or 12 through connections attached to fittings 15 and 16, while air may flow through the spaces or cells between the folds of the fins, thereby to effect the desired heat exchange.

Referring particularly to Fig. 3, it will be seen that each fold 21 of the fin strips 14 is formed, beginning a short marginal distance from front and rear edges, with a series of protuberances and depressions, or bumps, 22, 23, which project alternately in opposite directions from the plane of the fold. The bump 22 is shown as depressed into the plane of the paper, and therefore appears as a depression, while the bump 23 is shown as elevated, or as a protuberance. If the fold were viewed from the opposite side, then, of course, the depressions and protuberances would be reversed. In the direction from face to face of the core, the bumps merge into each other, as is indicated in Fig. 9. Each bump 22 or 23 overlies a similar bump in the next adjacent fold, and thus, from face to face of the core, there is provided an undulatory air path.

In the transverse direction, each bump is arcuate along its center section, as will be more readily apparent from Fig. 5, rising from edge to median and then decreasing to the opposite edge of the fold, to provide bumps all having the same height. Inasmuch as the underside of any bump forms either a depression or protuberance spaced from the immediately underlying protuberance or depression of the next fold, it will be readily understood that, in a section taken through the bump centers longitudinally of the fin, the arcuate lines merge into each other at the fold edges, to define an undulatory or more or less sinusoidal arc whose points of inflection, or reversal of curvature, lie in the edges.

It will also be noticed that the folds are laterally offset, to provide straight edge sections 24 against which the tubes 13 abut, and angularly disposed short spacer sections 25. These offsets are not very large dimensionally, but are sufficient to displace the tubes 13 approximately one-third to one-half a tube thickness, thereby plac-

ing the tubes in staggered relationship. At the points where the offsetting occurs, the adjacent bump 22 or 23 becomes slightly deformed, due to the action of the forming rolls or dies in displacing the metal. In Fig. 3, the offsetting of the folds is shown as progressing in one direction, while in Fig. 4 the offsetting is first in one direction and then in the other, and the offset distance is varied, so that no one of the tubes between any pair of fins is in alignment with any other between the same pair.

As also clearly shown in either Fig. 3 or Fig. 4, the tubes 13 are grouped into rows from face to face of the core, and are slightly staggered or offset by reason of the displacing of the folds. Each tube, which is relatively wide and of relatively narrow breadth, is located against the fin edges with the long dimension at right angles to the core faces, or with the narrow dimension disposed transversely thereof. While the tubes are thus staggered, they nevertheless overlap each other in the transverse direction, inasmuch as the offsetting is less than the tube breadth. They are also spaced from each other by the offset portions 25, which provide abutments to facilitate assembly and supports when the core is completed to resist adventitious displacement of a tube.

It has, of course, heretofore been proposed to provide secondary heat exchange surface in the form of spacer ribbons, in which the metal is deformed with bumps from face to face of the core to provide an undulatory air path. This is illustrated in my prior Patent No. 2,016,822 of October 8, 1935, in which is described a cellular automobile radiator. In the present instance, an even more effective air path is provided by causing the air to move in an up and down undulatory path and simultaneously displacing the air flow transversely. Whether this be explained on the hypothesis of turbulence or throttling of the air stream, the fact is that by offsetting the fin folds, and thereby placing the tubes in staggered arrangement, a more effective utilization of the air is obtained, thus adding to the capacity.

Another feature of the present fin ribbon is the extension of the bumps 22 and 23 to the edges of the folds, as is somewhat better shown in Figs. 5 and 6. After the ribbon stock has been deformed to provide the bumps and offset portions, it is gathered or folded into the generally zig-zag form shown in Fig. 5, and it may thereafter be compressed to bring the folds more closely together, as shown in Fig. 6. For an automobile radiator core, the tubes 13 will be spaced by the fins a distance of about half an inch, and if effective heat transfer is to be obtained, the tubes must tightly abut the fins at the straight edge portions 24 between adjacent folds. This means that the edges of the fins, designated by the reference numeral 26 in Figs. 5 and 6, are inclined to each other at an angle, which of course becomes progressively more acute as the fold spacing is decreased.

It has been discovered that, unless the fins are so constructed as to provide substantially fixed hinges at the junctions of the folds, then, upon bending to folded form, the actual line of bend will shift irregularly. It will be seen in Fig. 5 that there is a broken straight line T tangent to all bends, which represents excellent contact, and hence good heat transfer, between the fins and the tubes. In the instance of irregular shifting just referred to, the condition would be that one or two of the bends might have the desired

contact, but the next adjacent would either be spaced from the line T, or attempt to overlap it. With such irregular and uncontrollable displacements, all tubes cannot contact all fin edges in the desired manner, the core capacity therefore not only becomes less than desired, but it also becomes an uncertain variable.

According to the present invention, the extension of the bumps 22 and 23 to the edges of the folds imparts a measure of reinforcement to the metal, except at the actual region of bending, designated by the numeral 27 in Fig. 5. When the ribbon is pleated, there is therefore only a very limited distance between successive folds 15 through which the bend can be made, and this limited distance constitutes the fixed hinge just referred to. Inasmuch as the ribbon will bend along its line of least resistance, or the region 20 27, the folds will be uniform and the edges will be vertically aligned to contact the tubes uniformly. The provision of the hinge lines also permits some variation of the fold spacing without change in the forming dies.

In the form shown in Figs. 7 and 8, the fins are 25 provided with a series of folds 31 each having bumps 22 and 23 extending from edge to edge, as heretofore described. The hinge or bending section 32, however, in distinction to the bend section 27, is formed with an arcuate ridge 33 30 of short radius by outwardly creasing the bend section at this point. This further enforces the bending of the fins along predetermined lines to assure the desired uniformity of contact with the tubes 13. The transverse edge 34 of the fin 35 30 will therefore appear to merge into the arcuate ridges 33 through short connecting links 35, although the bumps 22 and 23 are contiguous with the ridges 33, reversing their direction of curvature at the ridges. It will also be understood 40 that the fin shown in Figs. 7 and 8 is also transversely offset, as explained in connection with Figs. 3 and 4.

After the ribbons have been formed, they are 45 bent at the hinge portions to provide the series 50 of folds, and are compacted to the extent required. Inasmuch as the bend line or hinge 27 or 33 is sharply defined, the fins readily retain their setting, whether it be say eight, ten, twelve, or even more folds per inch, and do not tend to 55 expand in spring-like fashion when released from the spacing tools. They may, however, be readily extended or further compressed, to provide wider or closer spacing. This feature is advantageous, not only in the handling of the fins 60 during assembly, but also when it may be desired to make a change of one or two folds per unit length of tubing. After forming, the fins and tubes are then bonded to each other in any of the well known manners.

The comparatively thin or hair line contact 65 between the edges 27 or 33 and the side walls of the tubes 13 has been found to be beneficial in providing tight joints with a minimum of solder. Under the compressive force required to hold the core elements in place during soldering, the several hinges or junctions between the folds bite into the tube walls, thus providing joints of 70 limited area, and accordingly decreasing the amount of solder required. Such tight joints are also effective in providing for heat transfer from the tube walls to the fin folds, inasmuch as there is less tube surface whose thickness is increased by the fin stock thickness.

While the invention has been described with reference to a few embodiments, it will be understood that it is not intended to limit it to any single one of them, or to exclude from its scope such variations and modifications as are encompassed by the following claims.

I claim:

1. A heat exchange core comprising spaced headers, a plurality of independent tubes having a narrow elongated cross section positioned between the headers, said tubes being grouped in rows from the front to the back of the core with their narrow dimension disposed transversely, the tubes in each row being offset from each other a distance less than said narrow dimension, said rows of tubes being spaced transversely of the core a distance greater than said narrow dimension, and continuous fins disposed between said rows and bonded to the tubes of adjacent rows, each of said fins comprising a strip of metal ribbon bent back and forth on itself to provide a plurality of spaced folds joined to each other by narrow edges, substantially imperforate bumps extending over the surface of each fold from the front to the back of the core, said bumps merging into each other, said bumps projecting alternately in opposite directions from the front to the back and between said narrow edges defining the limits of each fold, said narrow edges having straight portions having a length substantially equal to the long dimension of the tubes, said straight portions being connected by offset portions, whereby said narrow edges engage all of the tubes in said offset rows.

2. A heat exchange core comprising spaced headers, a plurality of independent tubes of narrow elongated cross section positioned between the headers, said tubes being grouped in spaced rows from the front to the back of the core with their narrow dimension disposed transversely, and continuous metallic fins disposed between the rows and bonded to the tubes of adjacent rows, each of said fins comprising a strip of metal bent back and forth on itself to form a series of spaced folds of equal width and having narrow edges engaging the long dimension of the tubes in adjacent rows, said folds being

formed to provide a series of substantially imperforate bumps extending from the front to the back of the core between said rows of adjacent tubes, said bumps merging into each other, adjacent bumps on each fold projecting in opposite directions from the plane of the fold, each of said bumps overlying a bump on an adjacent fold which projects in the same direction, thereby to form an undulatory air path between adjacent folds, said overlying bumps, in a direction longitudinal of the fin, having center sections defined by undulatory curves whose points of inflection lie in said narrow edges, said narrow edges constituting hinge lines about which said folds are bent.

3. A heat exchange core as set forth in claim 2, wherein said folds and said narrow edges are laterally offset between the tubes in each row a distance less than the breadth of the tube, thereby placing said tubes in staggered overlapping relation.

4. A heat exchange core as set forth in claim 2, wherein said narrow edges are outwardly creased to form ridges engaging the sides of the tubes and sharply defining the hinge lines.
